UNITED STATES PATENT OFFICE.

ROBERT BONNAVAL, OF PITTSBURGH, PENNSYLVANIA.

ELECTRICAL RADIATOR.

1,335,423.

Specification of Letters Patent. Patented Mar. 30, 1920.

Application filed August 30, 1919. Serial No. 320,926.

To all whom it may concern:

Be it known that I, ROBERT BONNAVAL, a citizen of the French Republic, at present time a resident of Pittsburgh, in the county of Allegheny and State of Pennsylvania, have invented a new and useful Improvement in Electrical Radiators, of which the following is a specification.

This invention relates to electric heating apparatus and its object is to generate the heat and simultaneously rapidly diffuse and radiate the same. The invention comprises a fan wheel associated with the secondary of an inductorium in a manner to diffuse or 15 dissipate the heat as rapidly as it is generated by the secondary of the inductorium.

In the accompanying drawing Figure 1 is a diagram illustrating the principle of generating the heat; Fig. 2 is a side elevation of 20 an apparatus for generating and diffusing the heat and showing associated control circuits diagrammatically; Fig. 3 is a face view of the preferred form of the fan wheel; Fig. 4 is a cross section through the core of the 25 transformer; Fig. 5 is a sectional view showing the manner of connecting the core to the base; and Fig. 6 is a detailed sectional view of a fan mounting showing a modification.

The principle according to which the heat 30 is generated is illustrated in Fig. 1, in which the reference numeral 1 indicates the iron core, preferably laminated, of a transformer, which, as illustrated, forms a complete closed magnetic circuit. Surrounding 35 one side of this core is the primary winding 2 of an inductorium, and around another side of the core is a ring or annulus 3, forming the secondary of an inductorium. Now, it is perfectly obvious that when an alternating current flows through the primary 40 winding 2 it induces a current in the ring or annulus 3, and that the current induced in the ring or annulus 3 is the product of the primary current (I_1) multiplied by the ratio of the number of turns of the 45 primary coil 2 to the single turn of the ring or annulus 3, which secondary current (I_2) can theoretically be made as large as is necessary by providing the necessary number 50 of turns in the primary coil, with respect to its inductance and to the reluctance of the magnetic circuit for the maximum flux density of the laminated iron core. The amount of heat evolved by the secondary 55 is proportional to the square of this sec-

ondary current, multiplied by the ohmic resistance of the ring or annulus, to wit,

$$Q = \frac{1}{j} R (I_2)^2.$$

60

If, now, the ring or annulus 3 be associated with a fan wheel, we will have an inductorium fan heater in which the heat is dissipated as rapidly as generated, thus heating a maximum quantity of air with the expenditure of a given amount of electric current. The apparatus illustrated by Figs. 2 to 6 is constructed according to this principle.

As illustrated in Figs. 2 to 5, the fan 70 heater comprises a base 4 which supports a suitable transformer core, preferably laminated, comprising the portions 5, 6, 7, 8 and 9, and which in turn supports an electric motor 10. The transformer core is suitably insulated from both the base 4 and the electric motor 10, such as by means of a fiber or similar connecting member 11, which may be arranged as shown in Fig. 5. Surrounding the portion 5 of the core is the primary 75 coil 2 of the transformer. Rotatably mounted upon the portion 7 of the transformer 4 is a fan wheel 12, having a hub 13 of fiber or other insulating material, to insulate it from the core and which is so constructed or formed as to provide a complete annulus (or a plurality of annuli) which forms the secondary of the transformer. This result may be secured by welding or otherwise suitably securing a closed 80 ring or annulus (one or more) to the blades of an ordinary fan wheel, or by forming the fan wheel as a disk, perforated centrally, and pressed or otherwise shaped to form 85 blades 14, as shown in Fig. 3. Such a fan 90 wheel obviously provides a closed annulus so that when alternating current flows through the primary winding 2, there will be induced in the fan wheel a secondary 95 current which is the product of the primary 100 current multiplied by the ratio of the number of turns of the primary coil 2 to the single turn of the secondary coil (the fan). The closed ring or annulus must be as close 105 as possible to the core to avoid high reactances. The ohmic resistance of the fan annulus is, of course, low, but since the current induced in it can be made of any value, theoretically, the amount of heat generated 110 can be made high, and this heat, when the

fan is revolved, will of course be rapidly dissipated. The amount of heat dissipated by the fan, per unit of time is a function of the speed of its rotation.

- 5 The fan wheel can be rotated in any suitable way from the motor 10, Fig. 2, showing intermeshing gears 15 and 16 on the motor armature shaft 17 and fan hub, respectively. Fig. 6 shows a modification in which the 10 motor is directly connected to the fan, such as by providing the fan hub with extensions 18 which are mounted in bearings 17^a formed in the core portions 6 and 8, respectively, and one of which extensions is suitably connected to the motor armature shaft 17. With this modification the core no longer forms a closed magnetic circuit (which will give the greatest output) but since the air gaps at the bearings 17^a are 15 small, the output is only slightly decreased. In fact, the core need not be a closed magnetic circuit. For instance, the portions 8 and 9 of the core might be omitted, or the portions 5 and 6 might be omitted. In the 20 latter case, the primary coil would be placed around either the portion 8 or 9. Likewise, all portions of the core except 7 might be omitted and in that case the primary coil would be around this portion 7 and the fan 25 mounted around the primary coil, or the primary coil mounted around the fan. But since there would be an easy leakage for the lines of magnetic force if the core were not substantially a closed magnetic circuit, it is 30 desirable to have it as nearly a closed magnetic circuit as possible.

In order to prevent magnetic leakage of the transformer itself and to maintain its output, there may be placed around the core 35 a copper shield 19, which, however, should not form a complete tube around the core, but left open, as shown in Fig. 4. A plurality of transformers may obviously be used. Likewise the secondary may be stationary, 40 the heat being removed by an ordinary ventilating fan running close to it.

The apparatus described may be controlled by an ordinary speed regulator in the motor circuit, but to maintain the temperature of 45 the fan constant it is also necessary to control the current through the transformer. An arrangement for regulating both the speed of the motor and controlling the temperature of the fan is shown in Fig. 2, in

which 20 and 21 indicate any suitable alternating current supply mains from which branches 22 and 23 lead to the primary winding 2 of the transformer and branches 24 and 25 lead to the motor 10. 26 indicates an insulating switch arm carrying a pair of contacts connected respectively with the mains 20 and 21 and coöperating with resistance contacts 27 and 28 in the branch circuits 23 and 25, respectively, so that thereby both the transformer and motor circuits are controlled. In the transformer circuit, at any suitable place, will be provided a suitable cut-out 29, so that, if desired, the current to the transformer may be suppressed and the fan used as an ordinary ventilator.

Obviously various arrangements of control circuits will suggest themselves to those skilled in the art. Neither do I limit myself to the specific construction and arrangement of apparatus shown, as the same may be readily varied without departing from the spirit of my invention.

I claim:

1. An inductive electric fan heater, the fan wheel of which is constructed to form the secondary of the inductorium.
2. An electric heater comprising the primary winding of an inductorium, and a fan wheel associated therewith and constructed to form the secondary of the inductorium.
3. An electric heater comprising the primary winding of an inductorium, and a fan wheel associated therewith and including a closed annulus forming the secondary of the inductorium.
4. An electric heater comprising a rotary fan including an annulus, a primary transformer coil, and a core common to said coil and fan annulus, whereby said annulus forms the secondary of a transformer.
5. An electric heater comprising an inductorium, a fan wheel associated therewith and constructed to form the secondary of the inductorium, an electric motor for rotating said fan, and circuits and mechanism arranged to control the amounts of current to the fan motor and to the inductorium.

In testimony whereof, I have hereunto set my hand.

ROBERT BONNAVAL.
